MOLD LINER ADAPTER FOR LINE CASTING MACHINES

David L. Anderson, Brooklyn, N. Y., assignor to Intertype Corporation, Brooklyn, N. Y., a corporation of New York

Application July 17, 1933, Serial No. 680,836
In Germany November 22, 1932

8 Claims. (Cl. 199—57)

The present invention relates to improvements in molds of the kind employed in line casting machines for casting type bars or slugs bearing characters along an edge thereof, such molds as 5 commonly used in line casting machines comprising a mold body and mold cap and liners interposed between the body and cap and defining the length and the height of the mold cavity and hence the length and thickness of the slugs 10 cast therein.

Molds of this kind have been equipped with plain surfaced caps for the casting of ordinary flat-sided or solid slugs and with recessed caps for the casting of skeleton slugs having relatively 15 large or extended type characters thereon. Such liners may be used for determining the length of the mold cavity and the spacing of the body and cap of a mold for casting the ordinary solid slugs which are of the smaller sizes, and the recessed cap of a mold may be spaced from the body 20 thereof by inserting liners of different thicknesses between such mold cap and body, one at each end, and by using liners of different lengths at one end of the mold, the length of the main 25 or body portion of the mold cavity may be varied. However, in using a recessed cap, while the ordinary flat liner interposed between it and the mold body can be of such length as to stop off the 30 length of the mold cavity at one or another desired point in order to vary the length of the 35 slug cast therein, such flat liner will not close or stop off the enlarged or recessed front portion of the cavity in which the character bearing shelf or overhang of the slug is cast. It has been proposed to provide a liner for molds having recessed 40 caps, which will stop off the length of the main cavity as well as the enlarged or recessed portion thereof in which the extended portion of 45 the character bearing edge of the slug is cast, but such liner has been of an angular or L-shape and hence could not be used in a mold having the ordinary plain surfaced cap for the casting of the ordinary flat-sided or solid slugs, and since 50 such special liners must be available in all required thicknesses and lengths and could be used only with recessed mold caps, the use thereof is expensive.

The primary object of the present invention is to provide means whereby the ordinary flat liners 55 commonly used for molds employing plain caps for casting solid small bodied slugs of different lengths may be adapted for use with recessed mold caps for stopping off the main portion of the mold cavity and also the extended or recessed front portion thereof in which the extended

character bearing portion of skeleton slugs is cast so that such liner will determine the length of both the body and character bearing extended portion of the slugs. In carrying out the invention, the ordinary flat liner is adapted to carry a 60 stop shaped to correspond to that of the extended or recessed front portion of the mold cavity to stop off the length thereof, such stop being detachable from the liner or otherwise removable from its operative position thereon so that the 65 same liner may be used interchangeably for molds with recessed caps for casting slugs with extended character bearing edges or for molds with the usual plain or solid caps for casting ordinary slugs, thus avoiding the expense of carrying stocks 70 of two different types of liners in all sizes.

In the accompanying drawing, which show the preferred embodiments of the invention:—

Figure 1 is a front elevation of a mold for line casting machines, provided with a liner embodying the present invention for determining the length of the mold cavity; 75

Figure 2 is a perspective view of a type bar or slug of the skeleton form and having an extended character bearing edge, as cast in a mold constructed as shown in Fig. 1; 80

Figure 3 is a collective view showing in perspective the left hand liner and insertable stop for use in a mold according to Fig. 1;

Figure 4 is a section through the mold, taken 85 on the line 4—4, in Fig. 1, and showing a portion of a matrix in position in front of the mold;

Figure 5 is a view similar to Fig. 4 but showing a modification of the shape of the extended or recessed front portion of the mold cavity; 90

Figure 6 is a perspective collective view of the left hand liner and stop suitable for use in a mold according to Figure 5;

Figure 7 is a perspective view of a type bar or slug of the skeleton form with extended character bearing portion, as cast in a mold constructed as shown in Figure 5; 95

Figure 8 is a perspective view of a portion of another form of liner, having the stop movably mounted thereon so that it may be swung upwardly into the position shown in this figure for use in a mold as shown in Fig. 5, and 100

Figure 9 is a view similar to Fig. 8 but showing the stop in inoperative position for use in ordinary molds for casting ordinary flat-sided or solid slugs. 105

Similar parts are designated by the same reference characters in the different figures.

The mold as shown in Figure 1 comprises as usual an upper part or cap 1, a lower part or 110

body 2 and the left hand and right hand liners 3 and 4, respectively, which space apart the cap and body members of the mold to form the continuous casting cavity 5 which is stopped off or closed by the inner ends 6 and 7 of these liners. The lower or casting face of the cap 1 is formed at intervals in its length with grooves 8 which extend upwardly from the casting cavity 5 and form the ribs 9 on the body portion 10 of the slug, as shown in Figure 2, and the front of the cap is bevelled to form a recess 11 which is extended upwardly from the cavity 5 at the front or matrix engaging edge of the mold, the extended character bearing edge 12 of the slug as shown in Figure 2 being cast in this recess.

The cap 1, however, has the recess 11 formed therein of a length suitable for the casting of a slug of maximum length which the machine may cast, and while a flat or ordinary liner 3 of the length, for example, shown in Figure 1, would stop off the portion of the mold cavity 5, it would not stop off or close the extended portion of the mold cavity formed by the recess 11 at the front thereof. The present invention provides an adaptor for the ordinary liner 3 which, when applied thereto, will serve in conjunction therewith to form a complete closure for the respective end of the entire front of the mold cavity. In carrying out the invention as shown in Figure 3, the ordinary flat liner 3, which determines the length of the mold cavity, is provided near its inner end with an aperture 13, and a stop in the form of a block 14 is provided which is beveled on one side and otherwise shaped to fit into the recess 11 in the front edge of the mold cap and to correspond in cross section with said recess, this block having a stem 15 thereon adapted to be removably inserted in the aperture 13 in the liner, so that when applied to the liner and the latter is inserted in a recessed mold as shown in Figure 1, the inner end 6 of the liner will stop off or close the main portion 5 of the mold cavity and the block 14 will stop off or close the recess 11 evenly with the inner end 6 of the liner.

In the embodiment of the invention shown in Figures 5, 6 and 7, the recess 11^a in the mold cap 1^a is square or rectangular in cross section so that it will cast a correspondingly shaped extended part 12^a on the slug as shown in Figure 7, and the liner 3 is adapted to receive a block 14^a of corresponding rectangular form to fit into and conform in cross section with the recess 11^a, the block 14^a having a stem 15^a to removably fit into the aperture 13 in the liner 3, as in the form of the invention shown in Figure 3.

In the embodiment of the invention shown in Figures 8 and 9, the stop block 14^b is of a thickness equal to the thickness of the liner 3^a and is rotatably connected thereto and fitted in a recess 3^b in the front edge of the liner by a pivot pin 3^c so that this block may be swung upwardly from the plane of the liner as shown in Figure 8 so that it will fit into and stop off the recess 11^a in the mold cap when the liner is used in a mold having such recessed cap, and this block may be swung downwardly into the plane of the liner as shown in Figure 9, thus adapting the liner for use in a mold having an ordinary plain or unrecessed mold cap for the casting of ordinary slugs. The block 14^b may be exchanged for one of a different length, for which purpose it is removable from the pivot pin 3^c.

In each instance, the stop block may be used with liners of different lengths and thicknesses. By providing the aperture 13 in the ordinary flat

mold liner, any shape of stop block to conform with a beveled, square or other shaped recess in the front of a recess mold cap can be employed in conjunction with such liner and thereby render the liner suitable for use in varying the length of the slugs cast in such molds. The presence of the aperture 13 in any liner obviously will not affect the utility of the liner for the ordinary plain or flat surface mold cap for casting solid bodied slugs. The provision of the stop block as a liner adaptor obviates the necessity of carrying special liners for recessed mold caps, or the necessity of employing mold caps recessed to different lengths in order to secure different length slugs of the skeleton form.

I claim as my invention:—

1. A mold for line casting machines having liners for determining the length of the slug body casting portion of the mold cavity, at least one of the liners carrying a stop formed separately therefrom and corresponding in shape with a recessed front part of the mold cavity suitable for casting slugs with overhanging type faces to limit the length of said front part of the mold cavity. 95

2. A mold according to claim 1, wherein said stop is exchangeably connected to the liner. 100

3. A liner for determining the length of the slug casting cavity of the mold of a line casting machine, and a stop carried by said liner and corresponding in shape with the recessed front part 105 of the cavity of a mold for casting slugs with overhanging type faces, said stop being adapted to occupy a position on the liner to limit the length of the recessed part of the mold cavity and being removable from said position to adapt 110 the liner to a mold having an unrecessed casting cavity.

4. A liner according to claim 3, wherein said stop is removable from said limiting position by detachment from the liner. 115

5. A liner according to claim 3, wherein said stop is removable from said limiting position by swinging into a different position on the liner. 120

6. A mold for line casting machines having liners for determining the length of the slug casting cavity therein, one of the liners having a thickness equal to the height of the slug body casting portion of the mold cavity, and a stop carried by the liner of a shape to conform with and fit into a recessed portion at the front of 125 the mold cavity for casting an overhanging character bearing portion on the slugs, to limit the length of said recessed portion, and removable from said position to adapt the liner to an unrecessed mold cavity. 130

7. In or for a line casting machine mold, liners for determining the length of the slug casting cavity of a mold of uniform height throughout its length, and means associated with at least one of said liners for carrying a stop formed separately 135 therefrom, said stop corresponding in shape with a recessed part of a mold having a cavity suitable for casting slugs with overhanging type faces and said stop being operative to limit the length of the recessed part of said last mentioned mold. 140

8. In or for a typographical machine, a mold having an unrecessed casting cavity, a mold having a recessed casting cavity, end liners normally operative to limit the length of said unrecessed mold cavity only, and means for rendering said 145 liners selectively operative to limit the length of either of said mold cavities.

DAVID L. ANDERSON.
